UNITED STATES PATENT OFFICE

CHARLES PFANSCHMIDT, OF CHICAGO, ILLINOIS, ASSIGNOR TO THEO. A. KOCHS CO.,
OF CHICAGO, ILLINOIS, A CORPORATION OF ILLINOIS.

DESIGN FOR A BARBER'S CHAIR.

No. 40,231.

Specification for Design.

Patented Aug. 17, 1909.

Application filed May 21, 1909. Serial No. 497,569. Term of patent 7 years.

To all whom it may concern:

Be it known that I, CHARLES PFANSCHMIDT, a citizen of the United States, residing at Chicago, in the county of Cook and State of Illinois, have invented a new, original, and ornamental Design for Barbers' Chairs, of which the following is a specification, reference being had to the accompanying drawing, forming part thereof:

The figure is a perspective view of a barber's chair showing my new design:

I claim:

The ornamental design for a barber's chair as shown.

CHARLES PFANSCHMIDT.
